UNITED STATES PATENT OFFICE.

BERT CARLISLE, OF SANTA ANA, CALIFORNIA.

AEROPLANE.

1,336,678.

Specification of Letters Patent. Patented Apr. 13, 1920.

Application filed January 14, 1919. Serial No. 271,098.

To all whom it may concern:

Be it known that I, BERT CARLISLE, a citizen of the United States, residing at Santa Ana, in the county of Orange and State of California, have invented new and useful Improvements in Aeroplanes, of which the following is a specification.

My invention relates to flying machines and consists of the novel features herein 10 shown, described and claimed.

An object of this invention is to construct an aeroplane provided with a single supporting plane having its major axis in the direction of flight, and which may be 15 quickly and easily tilted.

Another object of my invention is to provide a tilting lifting plane having means for indicating the angle at which the plane stands relative to the base, that is an angleo- 20 meter.

Another object of my invention is to construct a flying machine with a lifting plane pivotally mounted and having means for tilting the plane relative to the body of the 25 machine and so that when the operating means is released and the machine falls the lifting plane will automatically assume a horizontal position and serve as a parachute.

30 Other objects will appear hereinafter.

Figure 1 is a side elevation of an aeroplane embodying the principles of my invention and looking in the direction indicated by the arrows 1 in Figs. 2 and 3.

35 Fig. 2 is a horizontal section on the line 2-2 of Fig. 1 and looking downwardly.

Fig. 3 is a front elevation as indicated by the arrow 3 in Fig. 1.

40 Fig. 4 is an enlarged sectional elevation on a plane parallel with Fig. 1 and substantially on the line 4-4 of Fig. 3 and looking in the direction indicated by the arrow, parts being broken away to economize space.

Fig. 5 is an enlarged inside elevation of 45 the angleometer, the frame being broken away and the view being taken in the direction indicated by arrow 5 in Fig. 6.

Fig. 6 is a view in elevation at right angles to Fig. 5 as indicated by the arrow 6.

50 The body 1 of the aeroplane may be any of the usual constructions. The operator's cage 2 is open at the top and has a seat 3 across the rear side. The body 1 is mounted between side frames 4 and 5 and is connected to the side frames by pivots 6 and 7. The side frames 4 and 5 extend to a

considerable distance above the body 1. A pivot shaft 8 connects the upper ends of the side frames 4 and 5 and in a plane cross-wise with the line of travel and cross-wise 60 of the body 1. The lifting plane body 9 has bearings fitting upon the pivot shaft 8. The lifting plane body 9 is rectangular in plan and its length is several times its width. The side frames 10 and 11 of the 65 lifting plane body 9 are trusses of the double diamond type and serve to hold the lifting plane body stiff in a longitudinal direction. The side frames 10 and 11 are rigidly connected cross-wise. Guide shafts 70 12 and 13 are mounted in the side frames 4 and 5 equal distances forwardly and backwardly from the vertical plane of the pivots 6 and 7 and guide pulleys 14 and 15 are mounted upon these shafts. A tiller shaft 75 16 is mounted in the side frames 4 and 5 parallel with the guide shafts 12 and 13 and a short distance and forwardly from the seat 3 so that the tiller 17 upon the tiller shaft will be convenient to the operator 80 upon the seat 3. Pulleys 18 are fixed upon the tiller shaft 16 in line with the pulleys 14 and 15. Cables 19 are passed around under the pulley 18 upwardly over the pulleys 14 and 15 and outwardly and upwardly 85 and the ends of the cables are attached to the lifting plane body 9. The cables 19 are drawn taut and fixed to remain taut so that when the tiller 17 is operated the lifting plane body 9 will be tilted upon the pivot 90 shaft 8. The cables 19 will grip the tiller shaft pulley 18 and as the tiller is operated to rotate the pulley 18 one end of the lifting plane body will be pulled downwardly and the other end will be allowed to swing 95 upwardly and vice versa.

If the parts are properly proportioned the cables 19 will remain taut with the lifting plane body 9 at any possible angle of inclination relative to the body 1. If the 100 distance from the pivot shaft 8 to the upper outer ends of the cables 19 is twenty-four feet each way and the distance from the pivot shaft 8 straight down to the level of the guide shafts 12 and 13 is twelve feet 105 and the distance between the shafts 12 and 13 is fourteen feet, that is seven feet each way from the center, and the diameters of the pulleys 14 and 15 are about eighteen inches the cables 19 will lengthen one way 110 as much as they will shorten the other way and will remain taut all the time. Other

dimensions may be worked out to accomplish this result.

The cables 19 run freely and when the tiller 17 is released and the aeroplane starts 5 to fall the lifting plane will automatically assume a horizontal position and serve as a parachute.

Angleometer 20 is shown in detail in Figs. 5 and 6. A pulley 21 is rotatably mounted 10 upon the bolt 22 mounted in the side frame 4. An indicating dial 23 is fixed upon the side frame 4 concentric to the bolt 22 and has graduations 24 reading both ways from the vertical center 25. A hand 26 is fixed 15 to the pulley 21 and points to the graduations 24. A cable 27 is passed under the pulley 21 and the ends of the cable are passed upwardly and attached to the side frame 11 of the lifting plane body at the 20 points 28 and 29 so that as the lifting plane tilts upon the shaft 8 the pulley 21 will be rotated to carry the hand 26 and the angle of the lifting plane relative to the body 1 may be determined by the graduation at 25 which the hand 26 points. If the fixed diameter of the pulley 21 is eighteen inches then the points 28 and 29 should be thirty-six inches each way from the center of the shaft 8 so that the cable 27 will run tight 30 at all angles and so that the hand 26 will accurately show the inclination of the lifting plane.

Various changes may be made without departing from the spirit of my invention 35 as claimed.

I claim—

1. In a flying machine a main body; side frames extending upwardly from the main body; a lifting plane pivotally mounted at 40 the upper ends of the side frames; a tiller mounted near the lower ends of the side frames; a pulley rigid with the tiller; guide pulleys above the tiller shaft; a cable ex-

tending under the tiller pulley and upwardly over the guide pulleys and having 45 both ends attached to the lifting plane; the points of attachment of the cable to the lifting plane being twenty-four feet each side of the center of the pivot of the lifting plane and the level of the guide pulleys 50 being twelve feet below the level of the lifting plane pivot and the guide pulleys being seven feet each side of the vertical center; and the diameter of the guide pulleys being eighteen inches; so that when the tiller is 55 operated the cable will remain taut to tilt the lifting plane to any desired angle in either direction.

2. In a flying machine a main body; side frames extending upwardly from the main 60 body; a lifting plane pivotally mounted at the upper ends of the side frames; a tiller mounted near the lower ends of the side frames; a pulley rigid with the tiller; guide pulleys above the tiller shaft; a cable extending 65 under the tiller pulley and upwardly over the guide pulleys and having both ends attached to the lifting plane; the points of attachment of the cable to the lifting plane being forty-eight units of measurement each side of the center of the pivot of the lifting plane and the level of the guide pulleys being twenty-four units of measurement below the level of the lifting plane pivot and the guide pulleys being 70 fourteen units of measurement each side of the vertical center; and the diameter of the guide pulleys being three units of measurement; so that when the tiller is operated 75 the cable will remain taut to tilt the lifting plane to any desired angle in either direction.

In testimony whereof I have signed my name to this specification.

BERT CARLISLE.
